UNITED STATES PATENT OFFICE.

JOHN HERMAN HUNT, OF DAYTON, OHIO, ASSIGNOR TO THE DAYTON ENGINEERING LABORATORIES COMPANY, A CORPORATION OF OHIO.

ENGINE-STARTING SYSTEM.

1,281,363.

Specification of Letters Patent. Patented June 26, 1917.

Application filed September 3, 1914. Serial No. 859,969.

To all whom it may concern:

Be it known that I, JOHN HERMAN HUNT, a citizen of the United States of America, residing at Dayton, county of Montgomery, 5 and State of Ohio, have invented certain new and useful Improvements in Engine-Starting Systems, of which the following is a full, clear, and exact description.

This invention relates to an improvement 10 in electrical systems for internal combustion engines, and more particularly to systems of this type wherein an electric machine is driven as a generator or is operable as a motor for starting purposes.

15 One of the objects of the present invention is to provide a transmission mechanism or connecting devices between the electric machine and the combustion engine, which may be shifted into either its inoperative or 20 work positions without displacement of the electric machine.

Another object is to arrange the driving elements that one of said elements meshes with the other before the transmission mechanism 25 comes into contact with the driven element.

A further object relates to a means for shifting the connecting devices into such a 30 position for starting, that the contact between the connecting devices and the engine is increased until the speed of the engine becomes greater than the speed of the connecting devices, at which time said devices will be automatically thrown out of engagement 35 with the engine.

More specifically, the connecting devices are mounted on controlling means, so fulcrumed, that said devices are first oscillated, for a limited distance, on a floating center. 40 This movement connects the motor to the intermediate connecting devices. A further movement of these devices, oscillating about a stationary center, causes the intermediate connecting devices to come into engagement 45 with the flywheel, or any other suitable part of the engine.

Further objects and advantages of the present invention will be apparent from the following description, reference being had 50 to the accompanying drawing, wherein one preferred form of the present invention is clearly illustrated.

In the drawings:

Figure 1 is a fragmentary top plan view

of an automobile chassis and engine, includ- 55 ing one form of the present invention.

Fig. 2 is a view of the automatic clutch element mounted in the generator sprocket which is shown partly broken away.

Fig. 3 is an end view of the transmission 60 mechanism or the intermediate connecting devices and their component parts.

Referring to the drawing, the side frames of the chassis are indicated by the numeral 20. Between these frames and upon the cross members 21, the engine 22 is suitably mounted. This engine may be of any preferred type, the one shown in the drawing being of a four cylinder four cycle type, and is shown for the purpose of illustration only, 70 and is not to be considered in any way as a limitation of the invention.

The starting device 24 comprises an electric machine, mounted adjacent to the engine, and so arranged that one end of the armature shaft 25 is provided with a sprocket wheel 26, which is adapted to be connected to the sprocket wheel 27, by means of a flexible connection 28. The sprocket wheel 27 may be mounted directly on an extension of the crank shaft 29, or on any other shaft which may be connected with or 80 driven by said crank shaft.

The armature shaft 25 has an extension at its other end also, as at 30. This carries 85 the driving pinion 34 and forms the stationary fulcrum for the arm 35.

The other gear 32 of the connecting device is mounted upon a shaft 36, said shaft being secured to the control lever 33, which is pivoted to the floating shaft 38. Said control lever 33 has an extension 39 at its one end, to which is fastened any suitable operating element accessible to the operator of the machine. Another projection formed 95 at the opposite extremity of the lever 33, has one end of the spring 40 fastened thereto, the other end of said spring being fastened to the frame 20 of the chassis.

The lever 35 has a projection 41 so formed 100 that when the intermediate connecting devices are oscillated on the shaft 38, a limited movement of the said devices will bring a shoulder 43, formed on the lever 33, into contact with the face 41^a of the projection 41. A stop 42 is provided to limit the upward movement of the connecting devices caused by the spring 40. This stop can be 105

secured to any suitable part of the machine which will bring the same in alinement with the lever 33.

Another stop 44 is provided, which limits the downward travel of the arm 35, and is located in any suitable manner on the chassis of the engine.

Suitable automatic clutching or disconnecting elements are provided in the sprocket 10 26 and gear wheel 32, to make adjustments for the different ratios of speed. When the dynamo electric machine is cranking the engine, the clutching element 37 automatically connects the gear 32 with the friction element 15 31. At the same time, the clutch 26^a, (see Fig. 2), carried by the sprocket 26, automatically disconnects the dynamo electric machine from the engine at this point. The clutch 37 disconnects and 20 connects when the engine is running the dynamo electric machine as a generator.

The operation of the device is as follows:

When it is desired to crank the engine, the shaft 30 carrying the pinion 34, is caused to rotate by closing the initial motor circuit of the dynamo electric machine. The element 45 which is secured to the projection 39 of the lever 33, is depressed, which causes the connecting devices including a 30 gear 32 to oscillate on the center 38, along the arc 46 until the shoulder 43, formed on the lever 33, comes into contact with the face 41^a of the projection 41 on the lever 35. This movement will bring the gear 32 into mesh with the rotating pinion 34, causing the same to rotate.

Upon a further movement of the element 45, the connecting devices will oscillate on the stationary shaft 30, because the shaft 40 36, upon which the pressure is exerted through the elements 45 and 39, is located off the vertical plane of the center of the shaft 30. This causes the friction element 45 of the connecting devices to be brought into contact with the flywheel 47 of the engine. Any suitable circuit closing device may be employed to close the cranking circuit of the starting system, which adds a greater torque to the dynamo electric machine as 50 a motor.

Referring to Fig. 3, and noting the direction of rotation by the arrows, it can be seen that when the explosion engine is driven by the dynamo electric machine through the 55 friction disk 31, the resultant force will tend to increase the contact between the friction disk and the flywheel of the engine.

This force will be reversed after the engine becomes self actuating and the speed 60 of the flywheel exceeds that of the friction disk. In this case, the said disk will be forced or thrown out of contact with the flywheel.

While I have shown and described one

preferred form of the present invention, it should be understood that I reserve the right to make any changes or alterations as may come within the scope of the appended claims.

What I claim is as follows:

1. In a starting system for internal combustion or explosion engines, the combination with a power unit; connecting devices connected with said power unit and capable of movement to engage with the engine; and means for initially imparting movement to all of said connecting devices to bring certain of the devices into contact with the engine and to then impart a further movement to the device in contact with the engine to increase the pressure of the contact between the connecting device and the engine.

2. In a starting system for internal combustion or explosion engines, the combination with a starting device; connecting devices connected with the starting device and adapted to be forced into engagement with the engine, said devices comprising a pair of driving elements normally disengaged; and controlling means for effecting an initial movement to oscillate one of said elements to bring it into engagement with the other and having a final movement to further oscillate said first mentioned element into engagement with the engine.

3. In a starting system for internal combustion or explosion engines, the combination with a starting device; connecting devices adapted to connect said starting device with the engine; means for oscillating said connecting devices about a floating fulcrum for connecting the connecting devices to the starting device; and means for oscillating the connecting devices and the floating fulcrum about a fixed fulcrum to bring said connecting devices into engagement with the engine.

4. In a starting system for internal combustion or explosion engines, the combination with a starting device; connecting devices adapted to connect said starting device with the engine; means for oscillating said connecting devices for a limited distance about a floating fulcrum for connecting the said devices with the starting device; and means for oscillating the connecting devices and the floating fulcrum about a fixed fulcrum to bring said devices into engagement with the engine.

5. In a starting device for internal combustion or explosion engines, the combination with a starting device; connecting devices for coupling the starting device with the engine; means for oscillating said devices for bringing same into contact with the engine; means for restoring said connecting devices with their controlling elements, into their normal position; and stop devices for

limiting the scope of operation of the means for restoring the connecting devices to their normal position.

6. In a starting system for internal combustion or explosion engines, the combination with a power unit; connecting devices connected with said power unit and capable of movement to engage with the engine; means for initially imparting movement to 10 all of said connecting devices to bring certain of the devices into contact with the engine and to then impart a further movement to the device in contact with the engine to

increase the pressure of the contact between the connecting device and the engine; and 15 means for automatically returning the connecting devices to normal position when the speed of the engine becomes greater than the speed of the connecting devices.

In testimony whereof I affix my signature 20 in the presence of two subscribing witnesses.

JOHN HERMAN HUNT.
